W. H. RADEMAEKERS.
APPARATUS FOR DISINFECTING BOOKS, ETC.
APPLICATION FILED JUNE 16, 1916.

1,412,370.

Patented Apr. 11, 1922.

UNITED STATES PATENT OFFICE.

WILLIAM H. RADEMAEKERS, OF NEWARK, NEW JERSEY.

APPARATUS FOR DISINFECTING BOOKS, ETC.

1,412,370.

Specification of Letters Patent. Patented Apr. 11, 1922.

Application filed June 16, 1916. Serial No. 103,987.

To all whom it may concern:

Be it known that I, WILLIAM H. RADEMAEKERS, of the city of Newark, county of Essex, and State of New Jersey, have invented certain new and useful Improvements in Apparatus for Disinfecting Books, Etc., of which the following is a specification.

In public libraries, halls of record, etc., and all places where thin laminated sheets are promiscuously handled, especially in those in which books are taken out and put into circulation among the general public, in libraries schools, etc., it has long been recognized by librarians, school boards, and especially by boards of health, that they were a very great source for the wide dissemination of contagious and infectious diseases of all forms; and that for the preservation of the public health, and the prevention of epidemics of such diseases, proper methods, processes and apparatus for the complete and perfect disinfection and sterilization of such articles composed of laminated leaves, in a cheap, quick and efficient manner, that could be operated by unskilled labor, would be of the greatest value to the preservation of the public health.

To bring about such perfect and complete disinfection in such cheap and efficient manner is the main object of the apparatus I have herein disclosed. This I have brought about by my improved disinfecting apparatus herein first disclosed, described and claimed.

In disinfecting laminated articles or structures, such as books, etc., it has been the custom to pack them on shelves in large quantities in a room capable of being tightly sealed, and then to fill such room for a number of days with a disinfecting vapor or gas such as formaldehyde. But this process is very unsatisfactory, by reason of the fact that this operation of necessity takes up a large space, that the books or other articles for a considerable period of time cannot be used, (a very great detriment in all cases, especially in that of public record books and libraries) during which the books, etc., are not accessible to the general public, and also the fact that the disinfectant does not thoroughly penetrate throughout all the laminations of the various books or other articles.

In order to bring about a perfect disinfection it is absolutely essential that the dis-

infectant should be one that will not unduly stain or in any manner deteriorate the leaves or laminæ disinfected.

The great fundamental essential of my invention, lies in throwing between the leaves of a book or pack laminæ of any form, any suitable disinfectant, whether such disinfectant be powder, gas or nebulized vapor, or a combination thereof; and I accomplish this by fluttering the leaves of the book or pack of laminæ to be disinfected, and simultaneously throwing such disinfectant throughout the laminated body of leaves or book, while being so fluttered, in any manner and by any apparatus that will bring about the complete disinfection by such disinfectant, to the extreme back of the book or pack of laminæ.

My said improved apparatus for disinfecting books is fully shown, described and claimed in the following specification, of which the accompanying drawing forms a part, wherein similar letters or numerals of reference designate like or equivalent parts wherever found throughout the several views, and in which:

Fig. 1 is a front perspective view in elevation of my said improved disinfecting apparatus for books and other laminated articles.

Fig. 2 is a side view thereof partially in substantially vertical section, looking from the left of Fig. 1 in the direction of the arrow.

Fig. 3 is a top-plan view in detail of the book or laminæ pack-holder; and

Fig. 4 is a like view of the mechanism for vibrating such book holder.

It is, of course, self evident that the disinfectant of whatever form would in some cases be deleterious to the health of the operator by inhalation of the same. Therefore, to prevent escape of the waste vapor toward the operator, and into the operating room, a housing 1 is supported upon a baseboard 2, which housing is usually of the substantially semi-circular top form shown in Fig. 1, and is open at the front 3 as indicated in Fig. 2. In the back wall 4 of the receptacle, and usually adjacent to the top is an outlet orifice 5, usually of circular contour, in which is located a suction-fan 6, connected by a shaft 7, with a suitable motor 8, usually electric, as shown, having at the other end of the shaft 7, a gear wheel 9, meshing with a like gear-wheel 10, usually

of larger diameter, in operative connection with the drive-shaft 11, of the air compressor pump 12, connected by the air-pipe 13, with the air-tank 14, provided with a 5 pressure gauge 15, and a safety or release valve 16; and supported upon the board or support 2 adjacent to the front of the housing 1, is the holder 17, which may be of any form suitable to hold in position the books 10 or packs of laminæ particularly desired to be disinfected.

As shown herein, this bookholder of my invention is adapted to hold in proper position for disinfection, books of considerable 15 variance in size; and the same comprises a supporting standard 18, a book-shelf 19 from which extends upward at the center a book back-support 20, slightly curved, as indicated in Figs. 1 2 and 3, to receive the back 20 of the book, flanked on either side by the binder-board supports 21, which extend backward, as shown in Figs. 1, 2 and 3, at the end, and between these supports 21, and the back support 20, the binder-boards 23 25 (Fig. 3), of the book when in position are passed, so that they will rest against the back-side or face of the plates 21. In order that the inside of the binder-boards of the books may also be thoroughly disinfected at 30 the same time as the leaves, such plates 21 are usually provided with slots or perforations 24, which, however, are only shown in Figs. 1 and 2. The book-shelf 19 has attached to it in line with 20, a shaft 25 passing 35 down through the bottom part 2 of the housing, for vibrating the same, and while any suitable means may be used for bringing about such vibration, a good and efficient one therefor consists of a throw-lever 26, 40 having a pivot-pin 27 passing through a slot 28, in the inner and rear end of the actuating hand-lever 29, vibratorily secured to the underside of the bottom-board 2 of the housing by a stud-shaft or bolt 30, and it will be seen 45 that by vibrating the hand-lever 29, the bookholder 19 may be rapidly vibrated. Connected with the air-tank 14 by way of a nipple 32, is an air-hose 33 in connection with a nebulizing or atomizing device, comprising 50 a container for the fluidal disinfecting material 34, which is usually but not necessarily of the hand-controlled type shown, and is provided with a hollow handle 38, to which is attached the air-hose 33, leading to the 55 compressed air-tank 14; such handle being also provided with a normally closed spring air-valve 37, actuated by the thumb of the operator, by which the flow of the compressed-air to the nebulizing-nozzle 36, and 60 the consequent flow of the nebulized disinfectant to the leaves, etc., may be controlled as desired.

When disinfecting, the book having been placed in position upon the book-support, as 65 shown in Fig. 3, the container 34 is lifted by

the handle 38, and the valve 37 pressed open by the thumb, and the container then moved rapidly, both horizontally, vertically and diagonally, across the outer edges of the leaves, so as to direct the blast from the nebulizer thereof against the same at various angles back and forth, so as to simultaneously flutter the leaves, etc., and inject into, over and between the same such disinfecting blast, which will be driven throughout the 75 entire body of leaves, and into the remotest crevices at the back thereof; while at the same time none of the unhealthy disinfectant will reach the operator, as the spent gases of the blast will be constantly removed from the hood at the back and out through the exhaust-pipe by the suction-fan. The outside of the back and binding-parts are then sprayed in like manner, and the spray may be thrown down through between 80 and inside of the back of the book, as the back is then forced open.

When a gas is used for such disinfection the same is, of course, maintained under suitable pressure in a suitable tank, and such disinfecting gas may if desired be used in combination, and to nebulize a disinfecting liquid, or to air-blast into the part being disinfected a suitable disinfectant powder.

By the word "book" as used by me in the description and claims herein, I do not intend to limit myself to what are commonly known by that name, as it is evident that the improved disinfecting process and apparatus herein disclosed, may be applied to and used for the treatment of any and all leaved or laminated structures, of substantially similar form and construction, although not properly to be called "books."

I claim:

1. In a device of the class described, a support for a book; means for submitting the leaves of the book to a combined fluttering and disinfecting blast; and means for simultaneously withdrawing the surplus gas and nebulized disinfectant by suction.

2. In a device of the class described, a support for a book; a hood covering the support; means for submitting the leaves to a combined fluttering and disinfecting blast; and means for simultaneously withdrawing the surplus gases and disinfectants by suction from the hood at the rear.

3. In a device of the class described, a support adapted to hold a book thereon; with the cover in a substantially fully open position, means for fluttering the leaves thereof; means for simultaneously with such fluttering, throwing over and between such leaves fluidal disinfecting material; and means for constantly withdrawing the surplus disinfecting material by suction.

4. In a device of the class described, a support for supporting a single book; means

for vibrating the support and simultaneously fluttering the leaves; and by gaseous pressure blowing in and between the leaves a disinfecting fluidal material carried by the 5 gas; and means for simultaneously withdrawing the spent gas and disinfectant by suction.

5. In a device of the class described, a 10 housing; an exhaust-pipe connected with the housing; an air-pressure tank; an air-compressor pump adapted to maintain a constant pressure in the air-tank; a suction draft-fan to deliver the air drawn into the housing to the exhaust pipe; means for constantly actuating the air compressor and the 15 fan; a support within the housing for receiving a book; and a nebulizing device for simultaneously fluttering and disinfecting the leaves of such book or pack of laminæ, 20 connected with the air-compressor tank.

6. In a device of the class described, a 25 housing, an exhaust-pipe connected with the housing; an air pressure tank; an air compressor adapted to maintain a constant pressure in the tank; a suction-draft fan to deliver the air drawn into the housing to the 30 exhaust-pipe; means for constantly actuating the air-compressor and the fan; a support within the housing for receiving a book; a nebulizing device for simultaneously 35 fluttering and disinfecting the leaves of such book connected with the air-tank; and a single motor operating the air-compressor and the suction-fan.

35. 7. In a device of the class described, a book-holder comprising side-supports and a central standard to hold the back of the book, having slots through which the binder boards pass so as to lie behind the side supports adjacent thereto, and hold the leaves 40 in a practically open position, so that the same may be simultaneously fluttered.

8. In a device of the class described, a 45 book-holder comprising side supports, and a central standard to hold the back of the book having slots through which the binder boards pass so as to lie behind the side-supports adjacent thereto, and hold the leaves in a practically open position so that the same 50 may be simultaneously fluttered and disin-

fected, the back and side pieces of the support being perforated or slotted to permit of the passage of the disinfecting fluid to the back and binder-boards as well as the leaves.

55

9. In a device of the class described, a support adapted to hold a book thereon in a substantially vertical fully open position; means for fluttering the leaves thereof; means for simultaneously with such fluttering, throwing fluidal disinfecting material over and between such leaves; an exhausting hood with an air and book-inlet open toward the operator for preventing the disinfecting material from passing to the operator; and means for exhausting the surplus vapor and disinfecting material from the hood.

60

10. In a device of the class described, a support adapted to hold a book in a substantially fully open position; a nebulizer adapted to produce a blast of disinfecting fluidal material, nebulized by gas under pressure, and to direct such blast into, over and between the leaves, so as to simultaneously 65 flutter the leaves, and inject the blast there-between; and means for simultaneously exhausting the surplus gases and disinfectant.

70

11. In a device of the class described, a support adapted to hold a book in a substantially fully open position; a hood, open at the front, covering the support; a hand-controlled, movable, combined disinfectant container, and nebulizer adapted to produce a blast of disinfecting fluidal material nebulized by gas under pressure, and to direct such blast into, over and between the leaves, so as to simultaneously flutter the same, and inject the blast there-between; and means 75 for simultaneously withdrawing and exhausting the surplus gases and disinfectant from the hood at the rear.

80

Signed at the borough of Manhattan, city, county and State of New York, this 14 day of June, 1916.
